UNITED STATES PATENT OFFICE

2,677,232

COMBINATION PULSE JET AND RAM
JET ENGINEWhitney Collins, Grosse Pointe, Mich., assignor
to Continental Aviation & Engineering Corporation, Detroit, Mich., a corporation of Virginia

Application June 5, 1948, Serial No. 31,291

5 Claims. (Cl. 60—35.6)

1

This invention relates to jet engines, especially to the ram jet and pulse jet types.

A characteristic of ram jet engines is their inefficiency at low velocities. To be at all practical, ram jet engines have to be operated in the sonic or super-sonic ranges. Pulse jets operate with reasonably good efficiency in the sonic range, but cannot compare in effectiveness with ram jets above sonic speeds.

It is an object of this invention to provide a combination pulse jet and ram jet engine in which the engine operates as a pulse jet until some speed in or near the sonic range is reached, whereupon the engine begins to operate as a ram jet.

This and other objects are accomplished in an elongated housing open at both ends, the forward end of which may be held closed under certain conditions for operation as a pulse jet. When certain flight conditions obtain, the forward end opens up automatically and the engine operates as a ram jet.

In the drawings:

Fig. 1 is a longitudinal section of an engine made according to the invention, showing the housing in condition for operation as a pulse jet.

Fig. 1A is an enlarged fragmentary diagrammatic view of a pressure actuated control switch device.

Fig. 2 is a view in section of the extreme forward end of the engine, showing the engine in condition for operation as a ram jet.

Fig. 3 is an enlarged detail view of the pulse jet valves shown in Fig. 1, the valves being shown closed in Fig. 3.

Fig. 4 is a view similar to Fig. 3, but showing the valves open.

Fig. 5 is a performance curve showing comparative specific fuel consumption of ram and pulse jets plotted against air speed, and

Fig. 6 is a performance curve comparing the thrust of a pulse jet with that of a ram jet, plotted against air speed.

The jet engine of this invention consists of a single housing in which is disposed a pulse jet engine and a ram jet engine. The housing consists of an elongated member 2 being open at both ends. A plug 4 is positioned to close the forward end. The plug 4 is movable axially of the housing 2 in an inner body 6, the latter being supported by any suitable means such as struts 8.

A motor 10 is mounted in the inner body and is connected to move the plug 4 from its closed position as seen in Fig. 1 to its open position as seen in Fig. 2. Motor 10 may be any suitable electric motor, but it will be found convenient to utilize the fuel pressure as a motivating force. To that end, motor 10 may conveniently com-

2

prise a hydraulic cylinder in which a piston 10a is reciprocable to move the plug 4. The piston will preferably be spring biased in one direction, and suitable connections will be made from the fuel supply to the cylinder to move the piston against the spring bias.

Some suitable means will be provided to automatically activate the motor 10. The control means may for example be responsive to air pressure or to speed, or possibly to both air pressure and speed. As an example, a primary relay consisting of a pressure actuated micro-switch 12 may be located in the nose of the engine. This location may be in the movable plug as shown in Fig. 1. Pressure is communicated through passage 12a to diaphragm 12b, a spring 12c urging the switch contacts 12d apart against the resistance of the pressure on the diaphragm. A predetermined increase in pressure will close switch contacts 12d. A secondary relay 14 is connected by a suitable cable 16 to the primary relay 12. The secondary relay 14 may be a solenoid operated valve in a pipe connecting the hydraulic cylinder with the fuel tank, the solenoid 14a being energized on closing of the contacts 12d to move the valve 14b against the spring 14c to open the fuel pressure line to the cylinder of motor 10 to retract the piston 10a against the spring.

30 To provide for pulse jet operation, a plurality of valved air passages is provided in the housing somewhat back from the nose of the engine. These valved passages consist of a plurality of openings 18 provided in the housing 2, button type valves 20 to close the openings 18, and a screen 22 to hold the buttons in position.

Housing 2 encloses a combustion chamber 24 positioned to receive air from the valved air passages. A plurality of flame stabilizers 26 of any suitable design will serve to keep the ignited gas from blowing itself out. Fuel may be supplied in any suitable manner as by a fuel nozzle shown at 28. An igniter 30 may be provided to light the mixture at the beginning of operation.

45 Fig. 5 shows in a general way how the specific fuel consumption of a ram jet engine compares with that of a pulse jet engine. The curve 32 shows the consumption for a ram jet engine, and the curve 34 shows fuel consumption for a pulse jet engine. The point X is indicated as the point of intersection of the two curves. From the standpoint of maximum fuel economy, the control system of the motor would be set to open the front end of the engine tube at air speed S_1 .

50 It may be noted, however, that there might be other considerations. The curves shown in Fig. 6 illustrate the comparative thrusts of the two types of engine. The curve 36 illustrates the type of curve for a pulse jet engine, and the curve

38 illustrates the type of curve for a ram jet engine. These two curves are shown as intersecting at point Y, at air speed S_2 . S_1 and S_2 are not necessarily the same.

Operation

In operation, the controls for motor 10 will be set to keep the plug 4 in the closed position as shown in Fig. 1 for the purpose of getting the engine airborne and until it reaches a given speed. With plug 4 closing the forward end of the housing 2, the housing is in effect a pulse jet engine, with air entering the air passages in the housing according to the well-known cycle of pulse jet engines.

As soon as the engine attains certain pre-determined flight conditions, the motor controls operate to activate or energize the motor to make it move the plug 4 rearward to the position shown in Fig. 2, and to hold it in that position as long as the pre-determined flight conditions obtain. The housing then begins to function as a ram jet engine, during which time the pressure in the housing will be sufficient to keep the button valves 20 seated against the edges of the openings 18.

I claim:

1. In a power plant of the character described, an elongated engine casing having an internal combustion chamber and air inlet openings and valve means for said openings operable in response to pressure variations in said combustion chamber to open and close said valve means and thereby make said power plant become operable as a pulse jet engine, an air inlet opening in the forward end of said casing, valve means for said opening and means actuating said second mentioned valve means and operable to open said front end of said casing to the entrance of air to said combustion chamber and thereby make said power plant operable as a ram jet engine, said first mentioned valve means being closed by the substantially constant pressure developed in said combustion chamber under ram jet operation and means supplying fuel to said combustion chamber.

2. In a power plant of the character described, an elongated engine casing having an internal combustion chamber and air inlet openings and valve means for said openings operable in response to pressure variations in said combustion chamber to open and close said valve means and thereby make said power plant become operable as a pulse jet engine, an air inlet opening in the forward end of said casing, a valve means for said opening and means actuating said second mentioned valve means and operable to open said front end of said casing to the entrance of air to said combustion chamber and thereby make said power plant operable as a ram jet engine, said first mentioned valve means being closed by the substantially constant pressure developed in said combustion chamber under ram jet operation, and means supplying fuel to said combustion chamber, said means actuating said second mentioned valve means comprising control means therefor operable in response to a predetermined operation of said engine and to make said power plant inoperative as a pulse jet engine.

3. In a power plant of the character described, a housing consisting of an elongated tubular casing open at both ends and having a combustion chamber, a plug axially movably supported in said casing and operable to close or open the open front end of said casing, air inlet openings

in said casing for admitting air to the combustion chamber, means injecting fuel into said combustion chamber, valve means for said air inlet openings and operable in response to pressure variations in the combustion chamber when said plug is moved to a position closing the front end opening of said casing for making the power plant operate as a pulse jet engine, and means actuating said plug to move same to a position opening the front end opening of said casing, and control means for said plug actuating means and operable in response to a predetermined operation of said power plant to actuate the aforesaid plug actuating means to open the front end opening of said casing and thereby

make said power plant operable as a ram jet engine in which a substantially uniform high combustion pressure is continuously maintained in the combustion chamber sufficient to close said air inlet valve means and make said power plant incapable of operation as a pulse jet engine.

4. In a power plant of the character described, a housing consisting of an elongated tubular casing open at both ends and having a combustion chamber, a plug axially movably supported in said casing and operable to close or open the open front end of said casing, air inlet openings in said casing for admitting air to the combustion chamber, means injecting fuel into said combustion chamber, valve means for said air inlet openings and operable in response to pressure variations in the combustion chamber when said plug is moved to a position closing the front end opening of said casing for making the power plant operate as a pulse jet engine, and means actuating said plug to open or close the front end opening in said casing, said last mentioned means operable to make the power plant operate either as a pulse jet or a ram jet engine.

5. In a power plant of the character described, a housing consisting of an elongated tubular casing open at both ends and having a combustion chamber, a plug axially movably supported in said casing and operable to close or open the open front end of said casing, air inlet openings in said casing for admitting air to the combustion chamber, means injecting fuel into said combustion chamber, valve means for said air inlet openings and operable in response to pressure variations in the combustion chamber when said plug is moved to a position closing the front end opening of said casing for making the power plant operate as a pulse jet engine, and means actuating said plug to open or close the front end opening in said casing, said means operable to make the power plant operate either as a pulse jet or a ram jet engine, and an automatically operated control system for said plug actuating means and operable in response to a certain predetermined operation of said power plant.
